UNITED STATES PATENT OFFICE.

HENRY JOHN QUINCY, OF BROOKLYN, NEW YORK, ASSIGNOR TO ENGLANDER SPRING BED COMPANY, OF BROOKLYN, NEW YORK, A CORPORATION OF NEW YORK.

LOCKING MEANS FOR FOLDING COTS OR COUCH-BEDS.

1,157,254.

Specification of Letters Patent.

Patented Oct. 19, 1915.

Application filed June 13, 1914. Serial No. 844,840.

To all whom it may concern:

Be it known that I, HENRY J. QUINCY, a citizen of the United States, residing at Brooklyn, in the county of Kings and State of New York, have invented certain new and useful Improvements in Locking Means for Folding Cots or Couch-Beds, of which the following is a specification.

This invention relates to folding beds or cots, the object of the invention being to provide means whereby a particular form of cot or folding bed may be rendered practical so that in the use thereof the structure will not be collapsed by the weight of a person sitting upon either end thereof.

In the drawings accompanying and forming part of this specification, Figure 1 is a top view of this improved folding cot or bed with which the present improvement has to do; Fig. 2 is a side view thereof, the dotted lines illustrating the folding cot partly collapsed and without the improvement; Fig. 3 is a view of the folding cot when folded; and Fig. 4 is a perspective view of this improved locking means for rendering the folding cot practical.

Similar characters of reference indicate corresponding parts.

The improved folding bed or cot with which the present improvement has to do comprises a pair of frame sections 2 and 3 hinged adjacent to their opposed inner ends to a pair of hinge members or bars 4, which members are connected by a drop-formed cross bar 5, and each of these frame sections is provided with handles 6 for manipulating them.

Pivoted secured to each of the sections is a pair of legs or supports 7, and extending from the pair of legs of one section to the opposite section is a pair of diagonal braces or rods 8, the organization being such that these braces at each side of the cot cross each other adjacent to the hinge connection of the two sections. Connected to the frame sections by any suitable means, as helical springs 9, is a cot bottom 10, which may be of canvas or wire mesh as may be desired. By grasping the handles 6 the cot may be conveniently and readily folded from the full-line position shown in Fig. 2, through the dotted-line position shown therein, to the position shown in Fig. 3, so that it will take up but a very small space when not in use.

From the foregoing it will be observed that the foldable bed or cot comprises a pair of foldable cot sections pivotally connected adjacent to their inner ends to fold transversely by lifting such inner ends and allowing the outer ends to drop and close toward each other, and that each folding cot section has but a single pair of legs pivoted thereto, thus obviating the use of additional legs, pivots and connecting means therefor. This folding bed, however, has been proven in practice to have a serious defect, in that when a person sits upon either end the structure collapses as shown in dotted lines in Fig. 2, so that a person thoughtlessly sitting upon the structure is likely to be injured by being suddenly tipped off. To remedy this disadvantage and make the structure a practical one, I have provided means for preventing the collapsing of the structure, which means is very simple in its construction, readily applied to structures already made, and inexpensive to make and attach.

The locking means comprises a bent bar 11 pivoted at one end, as at 12, to the frame of one section and having a hook 13 at its opposite end for the reception of a pin 14 secured to the opposite section, this locking device being located in position at the hinge point of the folding cot section, one such locking device being at each hinge portion. This locking member is bent in the form shown in Fig. 4, that is substantially U-shaped, so as to overlap the hinge member to which the inner ends of the folding cot frames are connected. As this hinge member is shown as an angle iron plate the horizontal portion 11 of which overlaps the ends of the cot frame sections it is desirable that the locking member be of substantially the form shown in order to properly reach across this hinge member and hook into the pin 14 hereinbefore described. It will be immediately apparent that by this locking means the collapsing of the folding cot by any one sitting upon the end thereof is entirely prevented, as it is not possible for the folding cot sections to move upward at their pivoted ends, so that the liability of injury to the user is entirely avoided.

As hereinbefore stated, the present form of cot, having but a single pair of legs to each section, provides a very simple and comparatively inexpensive structure, but by

reason of the fact that each folding cot section has but a single pair of legs the structure when weight is placed on either end thereof immediately tends to collapse, so that 5 in order to use this simple form of supporting means for a structure of this kind I have found it essential to provide a means for preventing the collapse of the structure, and one form of means is shown herein as the 10 preferred form thereof, since it is particularly well adapted to this particular form of folding cot.

I claim as my invention:

1. In a folding cot, the combination of a 15 plurality of cot sections foldable transversely of the cot and spaced apart at their inner ends, a single pair of legs pivotally secured to each section between its inner and outer ends, a bar connecting each pair of 20 legs with the opposite section, a rigid hinge member pivotally connected to the inner ends of said sections for maintaining said sections spaced apart thereby to permit the legs and bars to be folded inside of said sections when the structure is folded, and means for locking the cot sections when unfolded thereby to prevent premature collapse thereof and comprising a locking device supported to swing in the plane of the 25 top of said cot.

2. In a folding cot, the combination of a 30 plurality of cot sections foldable transversely of the cot and spaced apart at their inner ends, a single pair of legs pivotally secured to each section between its inner and outer ends, a bar connecting each pair of legs with the opposite section, a rigid hinge member pivotally connected to the inner 35 ends of said sections for maintaining said sections spaced apart thereby to permit the legs and bars to be folded inside of said sections when the structure is folded, and means for locking the cot sections when unfolded thereby to prevent premature collapse thereof, said locking means comprising a bar pivoted to one of said sections and adapted to connect with the other of said sections across the top of said hinge member. 40

50 3. In a folding cot, the combination of a pair of cot sections foldable transversely of

the cot and spaced apart at their inner ends, a single pair of legs pivoted to each section nearer its outer than its inner ends, bars connecting the legs of one section with the 55 opposite section, a rigid hinge member pivotally connected to the inner ends of said sections to maintain said sections spaced apart thereby to permit the legs and bars to be folded inside of said sections when the 60 structure is folded, and means for locking the cot sections thereby to prevent premature collapse thereof and comprising a device located over the top of the hinge member. 65

4. In a folding cot, the combination of a pair of foldable cot sections, a rigid hinge member pivotally connected to and intermediate the inner ends of said sections, said member overlapping the tops of said sections, a single pair of legs for supporting each section, means connecting the pair of legs of each section with the opposite section, and means overlapping said hinge member and pivoted to one section and 70 shiftably connected to the other for preventing the premature collapse of the cot sections. 75

5. In a folding cot, the combination of a pair of foldable cot sections, a rigid hinge member at each side thereof to which the inner ends of the foldable cot sections are pivoted, said member overlapping the inner ends of said sections, a drop-formed bar connecting said members, a single pair of legs pivoted to each of said sections, a pair of brace bars pivotally connected to the pair of legs of each section and to the opposite cot section, and means adjacent to the hinge connections of the folding cot sections for 80 preventing the premature collapse thereof, said means comprising a bar pivoted to one section and hooked to the other, said bar 85 shaped to overlap the rigid hinge members. 90

Signed at New York, in the county of 95 Kings and State of New York, this 12th day of June, 1914.

HENRY JOHN QUINCY.
